UNITED STATES PATENT OFFICE.

JOHN B. ODELL, OF CHICAGO, ILLINOIS, ASSIGNOR OF ONE-HALF TO HORATIO
N. MAY, OF SAME PLACE.

ELECTRIC-RAILWAY APPARATUS.

SPECIFICATION forming part of Letters Patent No. 425,388, dated April 8, 1890.

Application filed November 30, 1889. Serial No. 332,153. (No model.)

To all whom it may concern:

Be it known that I, JOHN B. ODELL, a resident of Chicago, county of Cook, and State of Illinois, have invented certain new and useful 5 Improvements in Electric-Railway Apparatus, of which I do declare the following to be a full, clear, and exact description, reference being had to the accompanying drawings, forming part of this specification.

10 My present invention, while applicable, so far as certain of its features are concerned, to that system of electrical railways commonly known as the "multiple" system, in which the current from the generator is split up and 15 distributed through the motors of the various cars upon the route, is more particularly directed to the improvement of the system known as the "series" system, in which the main body of current is passed through the 20 motors of all the cars on the route.

My present invention has for its object, first, to improve the construction of the conduit within which will be placed the conductors for current, and within which will travel 25 the contact brushes or wheels that serve to deliver current from the conductors to the motors upon the cars.

A further object of my invention is to improve the construction of the arm that carries, 30 the contact brushes or wheels and the means for sustaining and operating said arm from the car.

A still further object of my invention is to provide improved means whereby the movement communicated from the motor of the car 35 to the driving-wheels can be graduated, in order to permit the easy starting and stopping of the car without necessarily diminishing the speed of the motor.

40 My invention also consists in a novel arrangement and connection of the conductors and means for controlling the passage of current therethrough.

These several objects of invention I have 45 accomplished by the novel construction hereinafter described, illustrated in the accompanying drawings, and particularly pointed out by the claims at the end of this specification.

Figure 1 is a view in vertical transverse 50 section through a subway embodying my in-

vention, this view illustrating in front elevation my improved construction of contact-arm and means for sustaining the same and the car embodying other features of my invention. Fig. 2 is a view showing in side elevation my 55 improved subway, and showing also the car and in side elevation the mechanism sustained thereby, portions of the car being broken away for purposes of better illustration. Fig. 3 is a diagrammatic view illustrating the improved 60 arrangement of conductors and means for controlling the passage of current therethrough. Fig. 4 is a detail view in side elevation of one of the yokes or braces of the subway or conduit.

65 The subway or conduit embodying my improved construction comprises a bottom formed of plates A, preferably of concavo-convex shape, that are sustained by means of suitable yokes or braces B, that are located 70 at convenient distances apart, the bottom plates A being in sections, the ends of which rest upon the correspondingly-curved portions of the yokes or braces and enter seats beneath the depending shoulders b of the 75 braces. The sides of the conduit are formed by the plates C, that are removably held within suitable flanges 2, projecting from the sides of the yokes B, and by preference the bottom edges of these plates C are sustained by the 80 flanges 3, also projecting laterally from the yokes. The top of the subway is formed by two plates D, that rest upon the upper ends of the arms of the braces B, the depending portions d of these plates D resting, preferably, upon shoulders 4, formed upon the outer edges of the braces B near their tops. The top plates D are separated a sufficient distance to form the usual slot, through which 85 can travel the arm that serves to carry the 90 contact wheels or brushes which take the current from the conductors within the conduit. The yokes or braces B are preferably formed or provided with the laterally-projecting flanges 5, to which will be bolted, as at 6, the 95 ends of suitable stringers E and E', preferably of wood, that serve to carry upon their lower edges the conductors F and F', through which current for the propulsion of the cars will be carried. The stringers E and E' will 100

be suitably insulated—as, for example, by coating the same with asphalt or in other well-known manner.

My purpose in forming the conduit with the removable plates C, preferably of sheet-iron, and removable cover-plates D is not merely to afford a simple construction of conduit, but to enable the interior of any part of the conduit to be more readily reached for the purpose of repairs than with existing constructions of conduits, and it is plain that when any section of the conduit or the conductors therein are to be repaired it is only necessary, after removing the paving and earth adjacent to the upper portion of the conduit, to lift off the top plates D and withdraw the side plates C, one or both, as may be necessary. The side plates C are by preference arranged in vertically-inclined position, and by preference the lower edges of these plates overlap the upper edges of the bottom plates A, since by such arrangement not merely is the water better deflected from the sides of the conduit, but the upper exposed portion of the conduit is made smaller and the plates are held in convenient position for ready withdrawal.

Within the subway or conduit and upon the conductors F and F' travel the contact brushes or wheels G and G', these wheels being preferably of copper and having their axles extending through and revolving in steel hubs or bushings 10, that are held within the yoke-shaped ends h and h' of the contact-arm H. The ends h and h' of this contact-arm are shown as formed of suitable insulating material—such as vulcanized fiber or the like—and between these arms are held the flexible contact-plates 20 and 21, that bear against the ends of the journals g. With these contact-plates 20 and 21 are connected, respectively, the ends of the conducting-wires 22 and 23, that are properly insulated and extend upwardly through the stem of the arm H and thence beneath the car to the respective binding-posts of the motor W. The upper portion of the stem of the contact-arm H is by preference rounded and passes through the brackets 30 and 31, that are sustained by the sectional journal-box 32, the brackets being held in position by the tie-rods 33, the upper ends of which extend through suitable holes within the angle-plates 34, that depend from the bottom 4 of the car. The upper portion of the stem of the contact-arm H is formed with a shoulder 36, against which bears the coiled spring 37, the opposite end of this spring resting upon the lower bracket 31, the spring thereby serving to lift the contact-arm, and consequently to hold the contact brushes or wheels G in proper bearing against the conductors F and F' within the conduit. My object in thus sustaining the contact-arm from the axle of the car is to avoid the motion which would be given to such arm if it were sustained by any part of the car subject to the action of the usual car-springs. The tie-rods 33, projecting through

the angle-plates 34, serve to hold the box 32 in proper position, while allowing for the motion of the car-body upon its springs.

In order to move the contact wheels or brushes G away from the conductors, I provide a throw-off lever K, pivoted at one end to a bracket k, and having its opposite end perforated and encircling the upper end of the stem of the contact-arm, and the movement of this lever K is effected by means of a screw-stem K', that passes through a threaded nut 38 and is controlled by means of a hand-wheel 39. From this construction it will be seen that when it is desired to move the contact wheels or brushes G away from the conductors F and F' it is only necessary to turn the hand-wheel 39, thereby causing the lever K to bear upon and depress the stem of the contact-rod H against the force of the spring 37. When, however, the throw-off lever K is released, the coiled spring 37 will restore the brushes or wheels G to proper bearing position against the conductors F and F'.

In order to effect the gradual starting and stopping of the car, I have provided improved means whereby the rotation of the motor-shaft x may be communicated to the drive-wheel Y without necessarily diminishing the speed of the motor, this being accomplished by connecting the motor and the drive-wheel by means of a variable friction device. I prefer to mount the motor W upon a movable base-plate W', that rests upon the rails 40 of the bed-plate 41 and is guarded against lateral movement by suitable side plates 42, and from the pulley of the motor-shaft leads a belt 50, that passes over the drive-pulley upon the axle of the drive-wheels Y. From this construction it is plain that if the motor be in such position with respect to the drive-pulley 51 as to cause the belt 50 to impart rotation from the motor to the drive-wheels, and it is desired to gradually stop the car, it is only necessary to gradually move backward the motor to such extent as to permit the belt 50 to slip more or less between the pulley of the motor-shaft and the drive-pulley until the belt ceases to transmit motion to the drive-wheels Y. In order to effect the movement of the motor, I prefer to provide a hand-lever M, pivoted, as at 60, to a frame 61, and connected at its lower end with the bed-plate of the motor by the rod 62, and provided with a suitable spring-pawl 63, that engages with the notched rim of the segment-plate 64, this pawl 63 being controlled by a suitable clutch-rod 65 in well-known manner. From this construction it will be seen that by merely moving the hand-lever M the motor can be shifted back and forth, and by means of the pawl and rack can be held at any desired position.

Referring to the diagrammatic view, Fig. 3, it will be seen that the conductors F and F' are arranged in separate sections or blocks suitably insulated from each other. Two sections only are illustrated, although it will be

understood that any desired number of sections may be employed, according to the length of the railway-line. The conductor F is connected by a wire 70 with the dynamo V, that is grounded, as at v, and from a point adjacent the end of the section of the conductor F leads a branch wire 71 to a resistance-coil 72, a wire 73 leading from this coil to a contact-point 74, against which a contact-point 75, carried by the armature 76, is at times drawn by a suitable spring 77. From the opposite end of this armature 76 leads a branch wire 78 to the end of the conductor F of the next block or section. From the conductor F' leads a branch wire 79 to a magnet 80, a wire 81 leading from such magnet and connecting with the branch wire 78.

Assuming the contact-points 74 and 75 to be together, as illustrated in Fig. 3 of the drawings, it is plain that the passage of current from the dynamo V will be in the direction of the arrows—that is to say, through the wire 70, the conductor F, the wire 71, the resistance-coil 72, the wire 73, contact-points 74 and 75, the armature 76, and branch wire 78 to the next adjacent section of the conductor F. When, however, a car carrying a motor passes onto a portion of the rod corresponding to the first sections of the conductors F and F', it is designed that the passage of current shall occur entirely through brushes or wheels of the contact-arm that bear against the conductors, so much of the current being delivered through the motor as may be necessary, while the remainder is automatically switched, so as to pass from the car to the conductor F'. In order to insure the passage of the current through the brushes or wheels of the contact-arm and through the branch wires 79 and electro-magnet 80, the operator of the car, as soon as the car comes upon the section of roadway corresponding with any section of conductors F and F', should operate the switch of his motor so as to permit the passage of current through the contact brushes or wheels and around the motor from the conductor F to the conductor F'. The instant that current is thus caused to pass from conductor F to conductor F' it will pass through branch wire 79 to magnet 80, thereby energizing this magnet and causing it to attract the armature 76, so as to break the connection between the contact-points 74 and 75 and prevent the passage of current through the branch wire 71 and resistance-coil 72. As this energization of the magnet 80 and consequent breaking of the circuit through the wire 71 is instantaneous, the operator of the car can immediately restore the switch, so as to cause the passage of current through the motor, in order to propel the car, and at such time the passage of current will be from the dynamo by way of wire 70, conductor F, through the contact portions and motor of the car to conductor F', and thence by branch wire 79, magnet 80, wire 81, and branch wire 78 to the next adjacent section

of the conductor F. As soon as the car has proceeded so far in its travel as to cause its contact-arms to pass from one section of the conductors to the next adjacent section the spring 77 will so move the armature 76 as to bring the contact-points 74 and 75 together, thereby permitting the passage of current through branch wire 71, resistance-coil 72, wire 73, armature 76, and branch wire 78 to the adjacent section of the conductor F. The current is thus delivered to the conductor F throughout each of the sections of the conductors along the route, and consequently any car upon any section will be supplied with current in the same manner as the car upon the first section.

If several cars should at any time be upon the same block or section of the conductors, the current would be divided between the motors of these cars, as in the "multiple" system. My object in employing a resistance-coil 72, as I prefer to do, is to insure the passage of current through the wheels or brushes of the contact-arm and magnet 80 when the operator of the car has switched out his motor, since if no such coil were employed there might be danger that the current, seeking the shortest course, would pass through wires 71 and 73, armature 76, and branch wire 78, instead of passing through the brushes or wheels of the contact-arm and branch wire 79 to the magnet 80.

While I regard the use of the resistance-coil as especially advantageous, I do not wish my invention to be understood as restricted thereto, nor to the precise construction of circuit controlling or switching mechanism by which the passage of current through branch wires 71 and 79 is determined.

Having thus described my invention, what I claim as new, and desire to secure by Letters Patent, is—

1. A subway or tunnel comprising suitable lateral braces arranged at convenient distances apart, bottom sections attached to said braces, removable side plates overlapping said bottom sections, and cover or top plates, substantially as described.

2. A subway or tunnel comprising suitable yoke-shaped braces arranged at convenient distances apart and having flanged sides, removable vertically-inclined side plates sustained by the flanges of said braces, and suitable top plates above said inclined side plates, substantially as described.

3. A subway or tunnel comprising suitable braces arranged at convenient distances apart, said braces having overhanging shoulders to retain the bottom sections in place, substantially as described.

4. A subway or tunnel comprising suitable braces arranged at convenient distances apart and provided with flanges and insulated stringers bolted to the flanges of said braces and provided with suitable conductors, substantially as described.

5. In an electric-railway car, the combina-

tion, with the contact-arm, of a suitable box for sustaining said arm, said box being carried by the car-axle, a spring for lifting said arm to hold its contact wheels or brushes against suitable conductors, and a pivoted throw-off lever for moving said brushes out of engagement with said conductors, substantially as described.

6. In an electric-railway car, the combination, with the car-body, of a contact-arm having a yoke-shaped head, brushes or wheels sustained by said head and having journals extending between the arms, and suitable conductors connecting said journals with the motor and the car, substantially as described.

7. In an electric-railway car, the combination of the drive-wheel, the motor sustained upon the car in a manner permitting it to be freely moved by the operator, and suitable connecting mechanism for uniting the drive-wheel and the motor-shaft, and suitable means for moving the motor back and forth in order to impart gradual movement therefrom to the drive-wheel of the car, substantially as described.

8. In an electric-railway car, the combination, with the motor sustained upon the car in a manner permitting it to be freely moved by the operator, of suitable means connected with said motor for moving the same back and forth and a belt for connecting the motor-shaft with the drive-wheel of the car, substantially as described.

9. In an electric-railway car, the combination, with a motor, of a movable base-plate for sustaining said motor, a hand-lever suitably connected with said base-plate for shifting the motor, and a belt for connecting the motor-shaft with the drive-wheel of the car, substantially as described.

10. An electric-railway system comprising main conductors arranged in series of insulated sections, branch conductors uniting the ends of both conductors of a section to the same conductor of the adjacent section, and a switch mechanism arranged to break the flow of current through one of said branch conductors and establish the flow of current through the other of said branch conductors, substantially as described.

11. An electric-railway system comprising a dynamo suitably grounded, main conductors, one of which is connected at one end with said dynamo and one of which is grounded at the opposite end of the line, said main conductors being arranged in series of insulated sections, branch conductors uniting the ends of both conductors of a section to the same conductor of the adjacent section, and a switch mechanism arranged to break the flow of current through one of said branch conductors and establish the flow of current through the other of said branch conductors when connection is made between said main conductors by the car, substantially as described.

12. An electric-railway system comprising main conductors arranged in series of insulated sections, branch conductors uniting the ends of both conductors of a section to the same conductor of the adjacent section, and a switch mechanism arranged to break the flow of current through one of said branch conductors and establish the flow of current through the other of said branch conductors, said switch mechanism consisting of an electro-magnet and contact-points interposed in the branch conductor that unites the end of the main conductor F of one of the sections to the main conductor F' of the adjacent section, substantially as described.

13. An electric-railway system comprising main conductors arranged in series of insulated sections, branch conductors uniting the ends of both conductors of a section to the same conductor of the adjacent section, a switch mechanism consisting of an electro-magnet and suitable contact-points to break the flow of current through one of said branch conductors and establish the flow of current through the other of said branch conductors, and a resistance coil or medium interposed in one of said branch conductors, substantially as and for the purposes set forth.
